PASTING MECHANISM

William E. Sharkey, Middletown, Ohio, assignor
to The Raymond Bag Company, Middletown,
Ohio, a corporation of Ohio

Application March 16, 1935, Serial No. 11,397

6 Claims. (Cl. 93—8)

This invention relates to pasting mechanism and is designed more particularly for applying to a bag a closure of the type shown and described in the application of John A. Finegan, Serial No. 2,484, filed January 19, 1935, and owned by The Raymond Bag Company, assignee of the present invention.

One object of the invention is to provide mechanism for pasting a folded tape for a portion only of its length over the open end of a bag.

A further object of the invention is to provide a mechanism for folding a continuous tape over the open ends of a series of bags and pasting the tape to a portion only of each bag end.

15. A further object of the invention is to provide a mechanism for folding a continuously moving tape over the open ends of a series of moving bags, pasting the tape to a portion only of each bag end and then severing the tape between adjacent bags.

Other objects of the invention will appear as the mechanism is described in detail.

In the accompanying drawings Fig. 1 is a plan view of a portion of a machine embodying my invention; Fig. 2 is a side elevation of that portion of the machine shown in Fig. 1; Fig. 3 is a sectional view taken on the line 3—3 of Fig. 1, and showing the paste applying device in elevation; Fig. 4 is a plan view of a portion of the tape with paste applied thereto; and Fig. 5 is a side elevation of a portion of a bag having the closure tape pasted thereto for a portion only of the width of the bag.

In these drawings I have illustrated one embodiment of the invention and have shown the same as applied to one side of a bag sewing machine. The other side of the machine, which is not shown in the drawings, is equipped with a sewing head for stitching the adjacent end of a bag, thus as the bags are fed through the machine they are stitched at one end and the tape closure folded over and pasted to the other end. It will be obvious, however, that the present invention may be utilized either in conjunction 45 with a sewing machine or separately therefrom.

The particular machine here illustrated comprises a main frame consisting of standards 10 on which is supported a table top 11 which is provided with an endless conveyor, which preferably 50 comprises a plurality of chains 12, one chain only being here shown, and these chains are provided with upstanding lugs 13 to engage the bags and move them through the machine. When the machine is in operation the bags are placed upon 55 the forwardly moving upper stretch of the con-

veyor immediately in front of the respective sets of lugs 13 so that they will be carried forward over the table by the conveyor. The lugs are spaced apart a distance somewhat greater than the width of the bags to provide a space between adjacent bags. It will be understood that the term "bags" as herein used, refers to the tubular bag sections, the ends of which have not yet been provided with closures.

As the bags are advanced by the conveyor a 10 continuous tape is folded about the open ends of the successive bags, which ends are in substantial alinement, and is attached to the bags, in the present instance by pasting the tape to both sides of the bag end for a portion only of the 15 width of the bag. As here shown, the tape is carried from a suitable source of supply, such as a roll 14, over guides, such as horizontal rollers 15 and 16 and a vertical roller 17, which latter serves to turn the web to a vertical position. 20 From the vertical roller 17 the web, which is indicated by the reference numeral 18, is carried through a folding device 19 which folds the same along its longitudinal center. The bag ends also pass through the inner portion of this folding 25 device and as the result the tape is folded about the open ends of the bags. Mounted adjacent to the tape guide 16 is a paste applying device 30 having a part adapted to be moved into and out of engagement with the tape so as to apply paste only to predetermined longitudinal portions of the tape, which portions are spaced longitudinally one from the other. In the present arrangement the paste applying device comprises a movable paste receptacle 20 which is preferably 35 mounted for movement about a pivotal axis 21 arranged approximately parallel with the paste 40 guide 16. Mounted in this receptacle and receiving paste therefrom is a paste applying element, here shown in the form of two rollers 22, 45 the lower portions of which move through the paste in the receptacle and the upper portions of which engage the tape on opposite sides of its longitudinal center and apply paste thereto. This 50 paste applying element moves with the receptacle when the latter is moved about its pivotal axis and is moved by the receptacle into and out of engagement with the tape. The point of contact between the paste applying device and the tape is preferably at the point where the tape is in engagement with the guide 16.

When the machine is in operation the paste applying element is retained in engagement with the tape for an interval determined in accordance with the travel of the tape so that paste 55

will be applied to a definite longitudinal portion of the tape. When this portion of the tape has been pasted the paste applying element is moved out of engagement with the tape and is retained 5 out of engagement therewith during a further movement of the tape sufficient to provide the desired spacing between the pasted portions. This movement may be imparted to the paste applying element in any suitable manner and, 10 in the present construction, the paste receptacle 20, which carries the paste applying element, is connected by a link 23 with one arm 24 of a bell crank lever which is pivotally mounted on the main frame. The other arm 25 of the bell crank 15 is pivotally connected with a thrust rod 26 slidably mounted in a bearing 27 carried by the main frame. At its rear end the thrust rod is provided with a roller 28, which bears against a cam 29, a spring 30 serving to press the roller against the cam and to retract the rod after it has been actuated by the same. The cam 29 is rotated in 20 definite timed relation to the travel of the bag conveyor 12 and this may be accomplished by mounting the cam on any suitable part of the driving mechanism for the machine as a whole, such as a shaft 31. The driving mechanism may 25 be of any suitable character, such as that shown and described in the patent to Sharkey No. 1,915,765, of June 27, 1933, and as it forms no part of the present invention it is not necessary to here show or describe the same. Separate feeding mechanism may be provided for the tape, if desired, but in practice I prefer to pull the tape 30 through the paste applying device and the folder by means of its connection with the bags which are being advanced by the conveyor. Consequently the cam 29 rotates in definite timed relation to the movement of the tape and the cam is so arranged with relation to the positions 35 of the bags on the conveyor that the pasted portions of the tape will be folded about and brought into engagement with the desired parts of the bag ends. Preferably the pasted portion of the tape is applied to the forward portion of 40 the bag and the pasted portions are of such length that the tape will be pasted to the bag for approximately two-thirds of the width of the latter, thus leaving the rear end of the tape free so that it may be moved upwardly to permit the 45 walls of the bag to be separated to provide a filling opening, as shown in Fig. 5. The pasted portions of the tape are shown at 32 in Fig. 4 and it will be noted that the pasted portions 32 are spaced apart lengthwise of the tape a distance sufficient to provide an unpasted portion 50 of the desired length.

In some cases the action of the folder upon the tape may be sufficient to cause the proper adhesion between the tape and the bag walls but I 60 prefer to provide a pressure device which will positively press the tape into engagement with the bag and cause the same to firmly adhere thereto. As shown in the drawings a pair of rollers 33 are arranged just beyond the folding device 19 and one of these rollers is yieldable so as to press the tape firmly into contact with the bag. When the device is applied to a sewing machine the sewing head may be retained and by removing the needle the presser foot may be used to 65 press the tape against the bag. When the tape has been pasted to the bags successive bags are connected one to the other by the intervening portions of tape and means are provided for severing the tape between adjacent bags to separate the latter. This severing means may be 70

of any suitable character, and, as here shown, it has a rotary head 4 carrying blades 35 and is intermittently operated in timed relation to the movement of the conveyor to sever the tapes. The severing device may be operated from any suitable part of the driving mechanism, a timing device 36 being interposed to impart the intermittent movement to the cutter head, all as shown in the Sharkey Patent No. 1,885,867, of November 1, 1932. 10

The viscosity of the paste is such that when the paste applying element is moved out of engagement with the tape a thin film or thread of paste may be stretched from the paste applying device to the tape and when eventually broken will engage the tape and extend the pasted portion beyond the desired limit. To avoid this I have provided means for severing this film of paste. For this purpose I have mounted a curved blade 37 above the guide roller 16 and have provided 15 means for moving the blade downwardly and causing the same to sever or break the paste film when the paste applying element is moved to its inoperative position. In the construction shown, the blade 37 is pivoted and is provided with a 20 crank arm 38 which is connected by a link 39 with one end of a lever 40 which is pivotally mounted between its ends on the main frame, as shown at 41, and the other end of its lever is connected with the link 23 which actuates the paste 25 receptacle. The arrangement is such that when the link 23 is moved downwardly to withdraw the paste rollers the link 39 will be moved upwardly to impart operative movement to the blade.

The operation of the apparatus will be readily understood from the foregoing description and it will be apparent that the movement of the paste applying element into and out of engagement with the tape at predetermined intervals causes paste to be applied only to spaced apart 40 longitudinal portions of the tape and that the pasted tape is then folded about the ends of the bags with the pasted portions in proper relation to the bag and is then pressed against the bag to cause it to adhere thereto. The mechanism is 45 very simple in construction and operation and can be produced at a low cost, or the paste applying mechanism may be readily applied to existing sewing machines or the like.

While I have shown and described one embodiment of my invention I wish it to be understood that I do not desire to be limited to the details thereof as various modifications may occur to a person skilled in the art. 50

Having now fully described my invention, what 55 I claim as new and desire to secure by Letters Patent, is:

1. In a machine comprising feeding means to advance a series of collapsed bags with their open ends in substantial alignment, and means 60 for folding a tape about the open ends of said bags; a paste applying device having a part movable into and out of engagement with said tape, means operated in timed relation to said bag feeding means to cause said part of said device 65 to intermittently engage said tape and apply paste to longitudinally separated portions thereof, and means to sever the paste film between said tape and said part of said paste applying device when said part is moved out of engagement with said tape.

2. In a machine comprising feeding means to advance a series of collapsed bags with their open ends in substantial alignment, and means 70 for guiding a continuous tape to and folding the 75

same about the open ends of said bags as they are advanced by said feeding means; a movable paste receptacle, a paste applying element mounted in said receptacle and adapted to engage said tape as the latter moves toward said folding means, means operated in timed relation to said bag feeding means to actuate said paste receptacle and cause said element to intermittently engage said tape and to apply paste to separated longitudinal portions thereof, and means actuated by the last mentioned means to sever the paste film when said paste applying element is moved out of engagement with said tape.

15 3. In a device for intermittently applying paste to a moving tape, a guide for said tape, a paste applying element, means for moving said element into and out of engagement with said tape at intervals determined in accordance with the 20 movement of said tape to cause paste to be applied only to longitudinally spaced portions of said tape, and means for severing the paste film between said tape and said element when said element is moved out of engagement with said tape.

25 4. In a device for intermittently applying paste to a moving tape, a guide for said tape, a movable paste receptacle, a paste applying element mounted in said receptacle and movable thereby into and out of engagement with said tape, a movable blade to sever the paste film between said element and said tape, and means for simultaneously moving said element out of engagement with said tape and causing said blade 30 to sever said paste film.

5. In a tape attaching machine, means for

feeding the tape in the direction of its length, a paste applying device having a part movable into and out of engagement with said tape as the latter is advanced by said feeding means, means operated in timed relation to said tape feeding means to cause said part of said paste applying device to intermittently engage said tape and apply paste to separated portions thereof, and means controlled in accordance with the movement of said part of said paste applying 10 device to positively interrupt the application of paste to said tape when said part is moved out of engagement with said tape.

6. In a machine comprising means for feeding a series of collapsed bags with their open 15 ends in substantial alignment and for feeding a continuous tape at the same speed that said bags are fed, means for folding said continuous tape about the open ends of said bags as they are advanced by said feeding means, a paste applying 20 device arranged in advance of said folding means and having a part movable into and out of engagement with said tape as the latter is advanced by said feeding means to apply parallel lines of paste to longitudinally separated portions of said 25 tape, and means controlled in accordance with the movement of said feeding means to so actuate said part of said paste applying device that paste will be applied only to those portions of said tape which are subsequently folded about prede- 30 termined portions of the ends of the respective bags and will not be applied to those portions of said tape which are folded about the remaining portions of the ends of said bags.

35

WILLIAM E. SHARKEY.
